ABSTRACT

A number input device for supplying a carry signal to a carry control circuit in controlling the carry of input numbers representing consecutive orders by single key operation, wherein there are generated by key means signals of input numbers representing prescribed consecutive orders. Said input key signals are conducted through a timing circuit to a carry signal generating circuit including a delay shift register which is operated by output from a clock pulse generator as well as by input key signals controlled in timing by output from said clock pulse generator, so as to supply a carry signal to the first one of the respective bits. The bit from which there is obtained a final carry signal by said carry signal generating circuit is connected in series to another bit from which there is successively produced a function signal.

FIG. 1

FIG. 2

A NUMBER INPUT DEVICE USING A MULTI-ZERO INPUT KEY

This invention relates to a number input device for supplying a carry signal to a carry control circuit in controlling the carry of input numbers representing consecutive orders by single key operation and more particularly to a type which produces a function signal in succession to a final carry signal.

In general business calculation using an electronic calculator, input numbers very often include numbers representing consecutive orders, for example, 1,000 or 500. Namely, it is rare that input numbers initially consist of, for example, 1,001 or 5,002. Accordingly, a ten-key type input number system is provided with a three-zero key or two-zero key to simplify key operation so as to realize the same effect as depressing the zero key two or three times simply by depressing it only once.

Where there is used said three-zero key or two-zero key during the arithmetic operation of a program to indicate the last group of orders of a given number, it is often required subsequently to operate keys associated with signals commanding functions, such as (+), (-), (X) and (÷). The conventional electronic calculator, therefore, is, as is usually the case, additionally provided with keys for generating particular function signals, presenting the drawback, for example, that key operation is complicated and has to be carried out many times.

It is accordingly the object of this invention to provide a number input device which generates a carry signal by depressing a multizero input key and subsequently a function signal.

To attain the above object, the number input device of this invention comprises a delay shift register for generating signals by a single key operation so as to carry input numbers in turn, the final bit of said shift register being connected in series to another bit such that there is produced a program processing signal consecutively upon generation of a carry signal from said final bit. Therefore, this invention eliminates the necessity of operating a function signal key until a certain portion of an input number is fully carried, thereby further simplifying key operation that has been possible in the past.

The present invention can be more fully understood from the following detailed description when taken in connection with reference to the accompanying drawing, in which:

FIG. 1 is a circuit diagram according to an embodiment of this invention; and

FIG. 2 is a chart showing the timing schedule of said embodiment.

The present invention will now be described with by reference to the appended drawing. Referring to FIG. 1, the terminal from which there is generated an input by operation of a three-zero key K_1 is connected to an input terminal of an AND circuit A_1 and of an OR circuit O_1 . The terminal from which there is produced an input by operation of a two-zero key K_2 is connected to an input terminal of an AND circuit A_2 and of said OR circuit O_1 . As used herein, the three-zero key is a device for generating input signals so as to carry input numbers representing three consecutive orders in succession by a single operation of said three-zero key. Likewise, the two-zero key is a device for generating input signals so as to carry input numbers denoting two

orders. The output terminal of the OR circuit O_1 is connected to one input terminal of an AND circuit A_3 through an input delay timing control circuit D consisting of delay type flip-flop circuits $D F/F.1$ and $D F/F.2$ as well as through an inverter I . The other input terminal of said AND circuit A_3 is connected to the junction of said delay flip-flop circuits $D F/F.1$ and $D F/F.2$. The output terminal of said AND circuit A_3 is connected to the other input terminals of said AND circuits A_1 and A_2 , respectively. The carry signal generating circuit R used in this invention is constituted by a shift register whose bits consist of series-connected delay flip-flop circuits having the same number as that of consecutive orders represented by input numbers. The shift register used in the embodiment of FIG. 1 comprises delay flip-flop circuits $SF-1$, $SF-2$ and $SF-3$ from which there are successively generated signals for carrying input numbers of at least three orders. It will be apparent that the number of orders represented by input numbers may be increased by addition of delay flip-flop circuits.

According to the above embodiment, said carry signal circuit means R and a flip-flop circuit $SF-4$ connected to the third one $SF-3$ of said circuit means R jointly constitute a two-phase dynamic delay type shift register of four bits.

The carry signal circuit means R is actuated by a read-in clock pulse ϕ_1 and a read-out clock pulse ϕ_2 both generated by a clock pulse generator G . These clock pulses ϕ_1 and ϕ_2 are produced at a sufficient interval to carry input numbers representing the consecutive orders one at a time. The output terminals of the clock pulse generator G are connected to the input clock pulse terminals of the flip-flop circuits $D F/F.1$ and $D F/F.2$ for operation of the input delay timing control circuit D consisting of said flip-flop circuits $D F/F.1$ and $D F/F.2$.

The output terminals of the respective bits of the carry signal circuit means R are connected to the input terminals of an OR gate circuit O_3 so as to supply a carry signal to a carry control circuit (not shown). To the terminal i of the first bit flip-flop circuit $SF-1$ is connected the output terminal of the AND circuit A_1 . To the terminal i of the second bit flip-flop circuit $SF-2$ are connected through the OR circuit O_2 the output terminals of the first bit flip-flop circuit $SF-1$ and of the AND circuit A_2 . The output terminal of the second bit flip-flop circuit $SF-2$ is connected to the terminal i of the third bit flip-flop circuit $SF-3$ which in turn is connected to the terminal i of the last flip-flop circuit $SF-4$, which supplies a program processing circuit (not shown) with a command signal S_2 .

There will now be described the operation of this invention by reference to the wave form diagram or timing chart of FIG. 2. There is taken the example where there is processed an addition program "18,000 + 14,000 + 125 =". Where such program is to be processed, the conventional calculator is operated by successively depressing the keys representing

[1], [8], [0 0 0], [P], [1], [4], [0 0 0], [P], [1], [2], [5], [P]

(P denotes a program processing key). In contrast, the calculator incorporating the present invention has only to be operated by successively depressing the keys representing

[1], [8], [0 0 0], [1], [4], [0 0 0], [1], [2], [5], [P],

requiring less key depressions than is required for the prior art apparatus.

Where there is depressed the three-zero key after the input number keys **1** and **8**, then said key generates a signal having a wave form indicated by FIG. 2(a) and supplies it to the AND circuit A_1 and OR circuit O_1 . The clock pulse generator G produces clock pulses ϕ_1 and ϕ_2 at an interval defined between FIG. 2(b) and 2(c) and supplies them to the flip-flop circuits $D F/F.1$ and $D F/F.2$ constituting the input delay timing control circuit D . Upon receipt of output from the OR circuit O_1 , the flip-flop circuit $D F/F.1$ generates a signal having a wave form shown in FIG. 2(d) and conducts it to the AND circuit A_3 . The flip-flop circuit $D F/F.2$ gives forth a signal having a wave form shown in FIG. 2(e) at a time delayed to the same extent as the interval at which there is produced the clock pulse ϕ_2 . However, outputs from the flip-flop circuits $D F/F.1$ and $D F/F.2$ are inverted in wave form by an inverter I . The AND circuit A_3 generates output bearing a wave form shown in FIG. 2(f) for a length of time corresponding to the interval between output from the delay flip-flop circuit $D F/F.1$ and output from the delay flip-flop circuit $D F/F.2$. Upon receipt of said output T , the AND circuit A_1 produces output having a wave form shown in FIG. 2(g) during the same interval. Output from the AND circuit A_1 is supplied to the terminal i of the first bit flip-flop circuit $SF-1$ of the carry signal circuit means R . When the AND circuit A_1 gives forth zero output, the first bit flip-flop circuit $SF-1$ generates output having a wave form shown in FIG. 2(h) until the shift pulse ϕ_2 arrives next time. Said output bearing the wave form of FIG. 2(h) is conducted as a carry signal S_1 through the OR circuit O_3 to a carry circuit (not shown). Upon arrival of the shift pulse ϕ_2 , the first bit flip-flop circuit $SF-1$ is reset and the second bit flip-flop circuit $SF-2$ is set to supply a carry signal bearing a wave form shown in FIG. 2(i) to the carry control circuit through the OR circuit O_3 , thereby carrying the data contained in the arithmetic operation register by one order. Then the third bit flip-flop circuit $SF-3$ is set to generate a carry signal having a wave form shown in FIG. 2(j) at a time delayed to the same extent as the interval at which the clock pulse ϕ_2 is generated. Accordingly, the OR circuit O_3 supplies a carry signal having a time width indicated by the wave form of FIG. 2(l) to the carry control circuit. When the third bit flip-flop circuit $SF-3$ is reset after producing output, the final bit flip-flop circuit $SF-4$ is set to generate a program processing signal S_2 having a wave form shown in FIG. 2(k) to carry out said processing. Upon completion of these three consecutive carry operations, there is automatically issued the succeeding function signal to process the input number portion "18,000 +" of an arithmetic expression by successive depression of the keys **1**, **8** and **0 0 0**.

Where the consecutive zero numbers represent two orders, there is depressed the two-zero key, output from which is supplied to the OR circuit O_1 and AND circuit A_2 . As described in connection with the preceding embodiment of three zero numbers, output from the OR circuit O_1 passes through the input delay timing control circuit D and inverter I to the AND circuit A_3 , output from which is supplied to the AND circuit A_2 .

together with the aforesaid input key signal. Signals having the wave forms indicated in FIG. 2 operate the carry signal circuit R at the intervals shown therein, together with output from the clock pulse generator G . 5 In this embodiment of two zero numbers of the consecutive orders, there are operated the second and third bit flip-flop circuits $SF-2$ and $SF-3$ of the carry signal circuit R to generate a carry signal S_1 through the OR circuit O_3 . Output from the third bit flip-flop circuit $SF-3$ sets the final bit flip-flop circuit $SF-4$. As in the preceding case, there is generated a program processing signal S_2 having the wave form of FIG. 2(k) to effect said processing.

The foregoing description relates to the separate operation of the three-zero and two-zero keys. While there may be provided a circuit for these two types of keys respectively, it is also possible to use a single circuitry covering the aforesaid two embodiments as illustrated in FIG. 1. Even such arrangement can be operated quite smoothly.

What is claimed is:

1. A number input device, comprising in combination:

a two-zero key;
a three-zero key;
counting devices operatively connected to said two-zero key and to said three-zero key;
an input number register;

means for supplying said input number register with a shift signal by operating said three-zero key and said two-zero key representing numbers of the orders of **1000** and **100**, respectively, through a corresponding number of said counting devices connected to said keys;

means for effecting a prescribed arithmetic operation when said input number register completes shifting after receiving said shift signal; and
said arithmetic operation being conducted by signals commanding a prescribed type of processing.

2. A number input device comprising, in combination:

a multzero key;
a counter operatively connected to said multzero key;

an input number register operatively connected to said counter;
means for left-shifting, by operating said multzero key, by an amount corresponding to the order of said multzero key, said left-shifting being accomplished by a shift signal which is fed as an input to said input number register through said counter; and

means for automatically issuing a function command to be succeeded immediately after said input number register completes said left-shifting operation.

3. A number input device according to claim 2, wherein said multzero key comprises a three-zero key representing the order of **1,000**.

4. A number input device according to claim 2, wherein said multzero key comprises a two-zero key representative of the order of **100**.
